MATERIAL HANDLING DEVICE

John S. Pilch, Ware, Mass.

Application December 18, 1951, Serial No. 262,231

5 Claims. (Cl. 214—138)

This invention relates to a new and improved material handling apparatus and has particular reference to new and improved features of such an apparatus adapted for embodiment in a loader, trencher, or similar type apparatus.

An object of the invention is to provide a new and improved material handling apparatus of the type set forth in which the loading or other dumping of the material being handled is facilitated.

Another object of the invention is to provide a new and improved device of the type set forth in which greater flexibility of the handling of the material is provided without requiring moving of the vehicle by which the apparatus is carried.

Another object of the invention is to provide a new and improved apparatus of the type set forth which apparatus may be tractor mounted and adapted to be actuated by the tractor power supply.

Another object of the invention is to provide a new and improved device of the type set forth which is entirely hydraulically actuated.

Another object of the invention is to provide a device of the type set forth having new and improved means for effecting removal of the material from the bucket.

Another object of the invention is to provide a new and improved device of the type set forth wherein the bucket, after being loaded, may be raised in a vertical and/or lateral direction as desired and thereby facilitating the loading of material thereby and increasing the speed of operation of the device.

Another object of the invention is to provide a material handling device in which the bucket may be moved in desired direction to facilitate and speed up the operation of the device.

Another object of the invention is to provide a new and improved device of the type set forth which is interchangeable with a tractor mounted loader and which embodies a considerable number of parts of the loader apparatus.

Another object of the invention is to provide a new and improved tractor mounted material handling device adapted for use as a loader or trencher, which is entirely hydraulically actuated and in which the bucket may be raised vertically and laterally to thereby facilitate and speed up the operation of the device.

Other objects and advantages of the invention will be apparent from the following description taken in connection with the accompanying drawings. It will be understood that changes may be made in the details of construction and arrangement of parts without departing from the scope of the invention as set forth in the accompanying claims.

Referring to the drawings:

Fig. 1 is a side view of an apparatus embodying the invention;

Fig. 2 is a front view thereof;

Fig. 3 is a top or plan view thereof;

2

Fig. 4 is a fragmentary front view, generally similar to Fig. 2, but showing a modified form of the invention;

Fig. 5 is a fragmentary sectional view taken on line 5—5 of Fig. 1, looking in the direction of the arrows; and

Fig. 6 is a view generally similar to Fig. 5 but showing the modified form of the apparatus of Fig. 4.

Referring more particularly to the drawings wherein similar reference characters designate corresponding parts throughout, the invention is shown applied to a tractor having the frame 10, wheels 11, and engine 12.

On the tractor or frame 10 are mounted the inverted V-shaped struts or supports 13, which are provided on opposite sides of the engine 12 and to each of which is pivotally connected the usual loader arm 14 at 15. The opposite pairs of struts 13 are connected between connecting rod 16 to the opposite ends of which are connected the struts 13 and the pivotal connection 15 for the arms 14.

On each of the pairs of struts 13 adjacent pivot 15 is provided a support 16 on which is pivotally mounted at 17 a dipper stick actuating cylinder 18 in each of which is positioned a piston on the rams 19.

On the frame 10, on each side of engine 12 is pivotally connected at 20 a cylinder 21 and to each of which extends a piston on rams 22 each of which are pivotally connected at their outer ends at 23 to one of the arms 14. These cylinders 21 and rams 22 are provided for raising and lowering the arms 14 and the mechanism carried thereby.

On the forward ends of arms 14 and rams 19 is located the support 24 which is pivotally connected at 25 and 26 respectively, to said arms 14 and rams 19 and dipper stick 27 is carried by said support 24.

Dipper stick 27 comprises a pair of spaced parallel supports 28 between the free ends of which is secured the bucket 29 which bucket as shown in the drawings has bottom and side walls only. The closure for the bucket or door 30 is connected to pivotable arm 31 by means of the supports 32 and arm 31 is pivotally connected at 33 between dipper stick members 28 on pivot 34 and said arm 31 has the extension 35 to which is pivotally connected at 36 the end of ram 37 on which is a piston extending into cylinder 38 which is pivotally connected at 39 to the upper end of plate 40 which is positioned between the members 28 of dipper stick 27 and which is pivotally mounted on support or plate 24 by the large stud 41.

The bracket or strut 42 is provided between arm 31 and extension 35 for reinforcing the construction and providing the same with greater rigidity.

It will be seen that with the movable or adjustable closure member 30 which is of substantially the size and shape of the open ends of bucket 29, but yet slightly smaller, so as to allow the moving of said member 30 through said bucket 29, that said closure may be utilized to close either end of bucket 29 depending upon whether the apparatus is to be employed for trenching or loading and also the member 30 may be used for emptying or dislodging material from the bucket 29 as hereinafter described.

In order to effect lateral movement of dipper stick 27 and bucket 29, plate or support 24 is provided with the supporting structure 43 which may be at one side of support 24 as shown in Figs. 2, 3 and 5, or may be positioned on the upper side thereof, as shown in Fig. 4 and to this reinforcing structure 43 is pivotally connected at 44 the end of cylinder 45 in which is a piston or ram 46 which is pivotally connected to pin 47 which extends through slot 48 and which pin is connected to plate 40 and adapted to effect pivotal movement thereof, within the range limited the slot 48 and length of cylinder and ram 45 and 46.

The hydraulic system is adapted to be actuated by the

usual hydraulic pump (not shown) carried by the tractor and the hydraulic fluid is supplied by tank 49. From said hydraulic pump, fluid is supplied under pressure to control valve 50 which is adapted to be controlled by the operator, through the operating levers 51, each of which is connected to one of the valve members 52 in control valve 50. Control valve 50 is connected to cylinders 21 by hydraulic lines 53 and 54 and to cylinders 18 by hydraulic lines 55 and 56. Control valve 50 is also connected to cylinder 38 by hydraulic lines 57 and 58 and to cylinder 45 by hydraulic lines 59 and 60 where upon operation of the proper operating lever 51, the corresponding control valve 52 will be actuated thereby supplying hydraulic fluid to actuate the piston and rams in desired direction to effect desired operation of the device.

It will be seen that with the apparatus as shown and described, that it is possible to operate dipper stick 27 and bucket 29 for trenching or loading provided the closure member 30 is in proper position within bucket 29 and also that it is possible to move dipper stick 27 laterally in either direction to allow loading or dumping of the material within the bucket without moving the vehicle on which the apparatus is mounted and further that by operation of ram 37 and cylinder 38, that closure member 30 can be actuated to effect removal of the material from the bucket 29 or to position closure member 30 in desired position within bucket 29.

In Figs. 2 and 4 as shown in dotted lines, the bucket is in various lateral positions. It will be apparent that the range of such lateral movement will be controlled through the length of slot 48, their ends of which act as stops and also the length of cylinder 45 and ram 46.

It is pointed out that by the use of the device of this invention that the apparatus may be employed for trenching or loading and that a much wider range of dumping of the bucket is provided without the necessity of any movement of the vehicle itself, which serves to considerably speed up and facilitate the operation of the device.

It will be seen that the dipper stick may be pivoted laterally regardless of the angular relation of the dipper stick and push arms thereby providing in effect a universal movement thereof giving much greater range of loading without movement of either the vehicle on which the apparatus is mounted or a vehicle to be loaded.

Also the apparatus may be mounted on any type vehicle and on the front or rear thereof.

From the foregoing, it will be seen that I have provided simple, efficient and relatively economical means for obtaining all of the objects and advantages of the invention.

I claim:

1. In a device of the character described, supporting arm means comprising a pair of arms extending axially of the vehicle and pivotally connected thereto, supporting means connected to said supporting arm means adjacent the free end thereof, connecting means connecting the free ends of said arms and means for pivoting said connecting means relative to said arms, a bucket carrying dipper stick pivotally connected intermediate its ends

15 to said supporting means for pivotal movement in a direction substantially parallel with the axis of said supporting arm means, hydraulically actuated means for pivoting said dipper stick in such parallel direction for digging, a second pivotal connection between said dipper stick and said supporting means whereby said dipper stick may be pivoted in a direction substantially normal to the axis of said supporting means, and hydraulically actuated means for pivoting said dipper stick in such normal direction for loading and means for limiting the extent of pivotal movement of said dipper stick in such normal direction, said means for limiting the extent of normal pivotal movement of said dipper stick comprising a curved slot on said connecting means and a pin on said dipper stick and extending into said slot.

2. A digger attachment adapted to be mounted on a vehicle, a supporting arm extending axially of the vehicle and pivoted thereto at one end, whereby the free end, remote from said vehicle, may be raised and lowered, support means pivoted to and extending vertically from said arm at its free end, means to rock said support about its pivot in the plane of the vehicle axis, a dipper-stick mounted on said support means and pivoted thereto on an axis normal to the said support means, and means to selectively rotate said dipper-stick on said axis whereby said dipper-stick may be swung into substantially horizontal position normal to the axis of said vehicle.

3. The digger attachment of claim 2 in which said means to rotate said dipper-stick on said axis comprises a hydraulic cylinder and piston means.

4. The digger attachment of claim 2 in which said means to rotate said dipper-stick on said axis comprises a hydraulic cylinder and piston means, a pin mounted on said dipper-stick eccentric to said axis, said pin passing through said support, said hydraulic means being secured at one end to said support and at the other to said pin.

5. The digger attachment of claim 2 in which said means to rotate said dipper-stick on said axis comprises a hydraulic cylinder and piston means, and means for limiting the extent of pivoted movement of said dipper-stick about said axis, said means for limiting the extent of such pivotal movement comprising an arcuate slot in said support and a pin extending therethrough.
